DESIGN FOR AN EMBROIDERED FABRIC

Lewis H. Hollander, New York, N. Y.

Application September 24, 1946, Serial No. 133,534

Term of patent 3½ years

(Cl. D92—1)

To all whom it may concern:

Be it known that I, Lewis H. Hollander, a citizen of the United States of America, residing in New York city, county of New York, and State of New York, have invented a new, original, and ornamental Design for an Embroidered Fabric, of which the following is a specification, reference being had to the accompanying drawing, forming part thereof, wherein the figure is a plan view of a piece of embroidered fabric showing my new design.

The background of the design is partially filled in for convenience of illustration.

I claim:

The ornamental design for an embroidered fabric, substantially as shown and described.

LEWIS H. HOLLANDER.
